UNITED STATES PATENT OFFICE

155,851

DESIGN FOR AN AIRPLANE

Albert G. Vojik and Calvin Thomas Ray, Baltimore, Md., assignors to The Glenn L. Martin Company, Baltimore, Md.

Application October 28, 1947, Serial No. 142,176

Term of patent 14 years

(Cl. D71—1)

To all whom it may concern:

Be it known that we, Albert G. Vojik and Calvin Thomas Ray, citizens of the United States and residents, respectively, of city of Baltimore, State of Maryland, and county of Baltimore, State of Maryland, have invented a new, original, and ornamental Design for an Airplane, of which the following is a specification, reference being had to the accompanying drawings, forming part thereof.

Figure 1 is a fragmentary perspective view, showing the interior arrangement of the forward entrance compartment in the airplane fuselage.

Figure 2 is a fragmentary section through the airplane fuselage, showing in plan the forward entrance compartment.

Figure 3 is a fragmentary section through the airplane fuselage, showing in elevation the forward entrance compartment.

Figure 4 is a fragmentary perspective view showing the interior arrangement of the forward entrance compartment in the airplane fuselage, showing in detail the arrangement of the galley.

Figure 5 is a top plan view of the entire airplane.

The characteristic features of our design reside in the portions, especially of the interior, shown by means of full lines in the drawing.

We claim:

The ornamental design for an airplane, substantially as shown and described.

ALBERT G. VOJIK.
CALVIN THOMAS RAY.
